UNITED STATES PATENT OFFICE.

JOHN MORE PETTUS, OF ONTARIO, CALIFORNIA.

TAIL-LIGHT SUPPORT.

Application filed February 21, 1924. Serial No. 694,371.

To all whom it may concern:

Be it known that I, JOHN M. PETTUS, a citizen of the United States, residing at Ontario, in the county of San Bernardino and State of California, have invented certain new and useful Improvements in Tail-Light Supports, and I do declare the following to be a full, clear, and exact description of the invention, such as will enable others skilled in the art to which it appertains to make and use the same.

My invention has for its object to provide a simple and inexpensive, yet a very desirable and efficient yieldable support for the tail-lights of trucks, trailers, and the like, the construction being such as to prevent excessive jarring of the tail-light with consequent injury to the bulb, the electrical connections for such bulb, etc.

With the foregoing in view, the invention resides in the novel subject matter herein-after described and claimed, the description being supplemented by the accompanying drawing.

Figure 1 is an elevation showing one form of the invention.

Figures 2 and 3 are sectional views as indicated by lines 2-2 and 3-3 of Fig. 1.

Figures 4 and 5 are elevations looking at opposite sides of a different form of the device.

Figure 6 is a vertical sectional view on line 6-6 of Fig. 4.

In Figs. 1, 2 and 3, the numeral 1 designates a rim frame of any desired shape, but preferably formed of angle metal as shown. One side of this frame is provided with a pair of extended attaching arms 2 for engagement with an appropriate bracket 3 carried by the truck or the like, the inner ends of these arms being secured to the frame in any desired manner, for instance, by providing them with threaded studs 4 passing through openings in the frame, and threading nuts 5 on the inner ends of said studs. Each of the arms 2 is bent laterally into U-shape, to receive the bracket 3 between its inner and outer arms 6 and 7, and a clamping screw 8 is threaded through the arm 7 to clamp the bracket against the arm 6.

By providing the attaching means shown

and described, it will be evident that severe tightening of the screws 8 will not have any tendency whatever to break the connections between the arms 2 and the frame 1, so that the device may be tightly secured in place without any danger of breaking the clamps from the frame, as might possibly occur with other forms of construction. I wish it understood however, that if desired, the frame might be attached in any other suitable manner.

Within the frame 1, I have shown a tail-light carrier in the form of a plate 9 which is preferably although not necessarily of circular form, said plate being connected with the frame by coiled springs or the like 10. The plate 9 is formed with a relatively large opening 11 to receive the wire connections 12 of an ordinary tail-light 13, and I have also shown a pair of openings 14 formed in said plate to receive the usual tail-light attaching bolts 15. Thus, one form of well known tail-light may be quickly and easily mounted upon the carrying plate 9.

In Figs. 4, 5 and 6, I have illustrated a frame 1^a of different shape, provided with attaching clamps 2^a for engaging the bracket 3^a. Within this frame, a contractible collar 9^a has been shown to carry the tail-light 13^a, said collar being connected by springs 10^a with the frame. The collar 9^a is adapted to be tightly secured around the tail-light and I have shown a clamping bolt 16, for contracting said collar around the tail-light casing. When this bolt is loosened the tension springs 10 expand the collar 9, permitting easy insertion or removal of the tail-light.

By employing either form of construction shown, or substantial equivalents thereof, the tail-light will be yieldably supported, eliminating danger of injuring the bulb or any of the electrical connections, even when driving over exceptionally rough roads.

As excellent results are obtainable from the constructions disclosed, they may well be followed, but within the scope of the invention as claimed, numerous minor changes may be made.

I claim:

A yieldable tail-light mounting comprising a continuous rim frame adapted to be

secured to an automobile, a transversely split tail-light embracing collar within said frame, a bolt for drawing the ends of said collar together to contract the latter around a tail-light, and coiled tension springs connecting said collar with said frame, the tension of said springs acting to expand the

collar when the bolt is loosened, permitting the tail-light to be easily inserted into or removed from said collar.

10

In testimony whereof I have hereunto affixed my signature.

JOHN MORE PETTUS.
